CLAIM

The ornamental design for a glass mountable antenna, as shown and described.

DESCRIPTION

FIG. 1 is a perspective view of a glass mountable antenna showing the new ornamental design;

FIG. 2 is a top plan view thereof;

FIG. 3 is a front side elevational view thereof, the rear side view being a mirror image thereof;

FIG. 4 is a left end elevational view thereof;

FIG. 5 is a right end elevational view thereof; and,

FIG. 6 is a bottom plan view thereof.
